UNITED STATES PATENT OFFICE.

CARL J. SCHWARZE, OF ADRIAN, MICHIGAN, ASSIGNOR TO SCHWARZE ELECTRIC COMPANY, OF ADRIAN, MICHIGAN, A CORPORATION OF MICHIGAN.

ELECTRIC BELL.

1,265,393.

Specification of Letters Patent.

Patented May 7, 1918.

Application filed September 1, 1917. Serial No. 189,259.

To all whom it may concern:

Be it known that I, CARL J. SCHWARZE, a citizen of the United States of America, residing at Adrian, in the county of Lenawee 5 and State of Michigan, have invented certain new and useful Improvements in Electric Bells, of which the following is a specification, reference being had therein to the accompanying drawings.

10 The invention relates to electric bells and more particularly to that type in which a round bell is mounted upon a round base. The invention comprises certain novel features of construction as hereinafter set forth.

15 In the drawings:

Figure 1 is a plan view of the base with the bell removed;

Fig. 2 is a longitudinal section through the base and bell;

20 Fig. 3 is a transverse section.

A is a base formed of pressed sheet-metal having a marginal circular and rearwardly-extending flange B terminating in a laterally-extending portion C, and having at one 25 or more points laterally-extending perforated ears D forming securing means therefor. This base is also provided with a circular depressed panel E cut away at one point F. G is a yoke-shaped member having its ends 30 G' reduced in width and threaded, said ends extending through perforations in the panel E of the base and being secured thereto by clamping nuts H. I is the bell which is centrally secured to the yoke G by a screw I'.

35 J is a Z-shaped member of magnetic material, such as soft iron, the central portion J' thereof being secured to the depressed panel E, with the rearwardly-extending flange J² projecting through the aperture F, 40 and the flange J³ projecting outward from said depressed panel. K are magnetic core-pieces secured to the flange J³ and extending parallelly above the depressed panel. L are magnetic coils mounted on said core-pieces.

45 M is a bridge of non-magnetic metal extending between the opposite ends of said core-pieces. O is a striker-bar slidably mounted in alined apertures in the flange J³ and non-magnetic bridge M. P is an armature secured 50 to said striker and extending on opposite sides thereof in proximity to the poles of said magnet. This armature has an outwardly-extending portion Q which is returnbent. R is a resilient vibrator mounted on the rear-

wardly-extending flange J² and extending 55 outward through the aperture F into the returnbend Q of the armature. The vibrator R forms a grounded electrode having a contact S mounted thereon, and T is an insulated electrode having a coöperating contact T'. The electrode T is also mounted upon the rearwardly-extending flange J², being insulated therefrom and extending outward through the aperture F. U are 60 terminal posts mounted on the peripheral flange of the base and extending radially outward therefrom. In operation the circuit 65 is closed through the coöperating contacts S and T' and is broken by the movement of the armature, and returnbent portion U 70 thereof actuating the vibrator to withdraw the contact S. This will impart a rapid reciprocation to the armature and to the striker-bar O, which latter is arranged with its free end in proximity to the inner edge 75 of the bell. Thus during the reciprocation of this striker a succession of blows will be struck upon the bell.

What I claim as my invention is:

1. An electric bell, comprising a circular 80 base formed of pressed sheet-metal having a marginal rearwardly-extending flange and a centrally depressed panel, a U-shaped yoke having its ends engaging perforations in said depressed panel and secured thereto, the 85 central portion passing diametrically across said base, a bell centrally secured to said yoke and covering said depressed panel, an electro-magnet mounted within the yoke, an armature, a slideable striker on which said 90 armature is mounted having its free end extending in proximity to the margin of said bell, and a vibrator for imparting a reciprocatory movement to said armature and striker. 95

2. An electric bell, comprising a circular base formed of pressed sheet-metal having a marginal rearwardly-extending flange and a central depressed panel, a U-shaped yoke having its ends secured to said depressed 100 panel on diametrically opposite sides thereof and a central portion extending across said panel above the same, a bell centrally mounted upon said yoke and covering said depressed panel, an electro-magnet mounted 105 within said yoke upon said depressed panel, a reciprocatory striker-bar extending parallel to said depressed panel and centrally of

said magnet, its outer end being in proximity to the margin of said bell, an armature mounted on said striker bar, and a vibrator coöoperating with said armature to cause the 5 reciprocation thereof.

3. An electric bell, comprising a base formed of pressed sheet-metal having a circular marginal flange extending rearward with laterally-extending perforated portions 10 forming securing means, the central portion of said base having a depressed panel cut away at one point, a U-shaped yoke having its ends secured to said depressed panel at diametrically opposite points and a central 15 portion extending across the panel above the same, a bell centrally mounted on said yoke, an electro-magnet mounted on said base within said yoke and comprising a Z-member the central portion thereof being secured 20 to said panel, one of the flanges extending outward from said panel and the other flange extending rearward through said

aperture, magnet cores secured to said outwardly-extending flange and arranged parallel to each other and said depressed panel, 25 a non-magnetic bridge extending between the outer ends of said core pieces, a striker bar slidably secured in alined apertures in said outwardly-extending flange and non-magnetic bridge, the outer end of said striker 30 being in proximity to said bell, an armature mounted on the opposite end of said striker and provided with a return-bent portion, a vibrator mounted on said rearwardly-extending flange of said Z-member and extending 35 outward through said aperture into engagement with the returnbent portion of said armature, and an insulated electrode also mounted on said rearwardly-extending flange and extending outward through said 40 aperture into operative relation to said vibrator.

In testimony whereof I affix my signature.
CARL J. SCHWARZE.
